(57) **CLAIM**

The ornamental design for a lantern, as shown and described.

DESCRIPTION

FIG. 1 is a top, front perspective view of the lantern of the present invention showing the new design;

FIG. 2 is a bottom perspective view thereof;

FIG. 3 is a front elevation view thereof;

FIG. 4 is a rear elevation view thereof;

FIG. 5 is a side elevation view thereof;

FIG. 6 is a side elevation view thereof, showing the opposite side of FIG. 5;

FIG. 7 is a top plan view thereof; and,

FIG. 8 is a bottom plan view thereof.

The broken lines are directed to environment and are for illustrative purposes only, thus forming no part of the claimed design. The present application claims priority to U.S. Application Ser. No. 29/193,108, filed Nov. 3, 2003, by the same inventors.
